(57) **CLAIM**

The ornamental design for a hoist, as shown and described.

DESCRIPTION

FIG. 1 is a front perspective view of a hoist showing my new design;

FIG. 2 is a rear perspective view thereof;

FIG. 3 is a first side view thereof;

FIG. 4 is a rear view thereof;

FIG. 5 is a second side view thereof;

FIG. 6 is a front view thereof;

FIG. 7 is a top view thereof; and,

FIG. 8 is a bottom view thereof.

The broken lines in the figures are for the purpose of illustrating portions of the hoist which form no part of the claimed design.

1 Claim, 5 Drawing Sheets(56)
